[57] CLAIM

The ornamental design for a safety chain holder, as shown and described.

DESCRIPTION

FIG. 1 is a perspective view of a safety chain holder, showing my new design, the hinged cover being shown in open position;

FIG. 2 is a partial median vertical longitudinal sectional view with the hinged cover in closed position, the broken lines illustrating a portion of a safety chain located within the holder forming no part of the design;

FIG. 3 is a top plan view, showing the hinged cover in closed position;

FIG. 4 is an elevational view of one end, with the hinged cover in closed position the opposite end being substantially a mirror image thereof; and,

FIG. 5 is a bottom plan view.
